ATTORNEY

UNITED STATES PATENT OFFICE.

LEOPOLD STIASSNY, OF NEW YORK, N. Y.

LIGHT-DISTRIBUTER.

No. 911,458

Specification of Letters Patent.

Patented Feb. 2, 1909.

Application filed February 5, 1908. Serial No. 414,393.

To all whom it may concern:

Be it known that I, LEOPOLD STIASSNY, a citizen of the United States, residing at New York, in the county of New York and State of New York, have invented new and useful improvements in Light-Distributers, of which the following is a specification.

This invention relates to a lamp having a lens or light distributer suspended a suitable distance below the chimney to allow ventilation.

The lens is suspended by means of flexible connections either inside or outside the globe, such connections or chains being usually attached inside but in case of a small globe or when for other reasons the attachment cannot be thus made the suspending means are applied at the outside.

This invention is set forth in the following specification and claims and illustrated in the annexed drawing, in which:

Figure 1 represents a vertical section of a lamp embodying this invention. Fig. 2 is a similar section of a modification. Fig. 3 shows a detail edge view of a ring.

By means of this invention a lamp such as an inverted incandescent gas or electric light has its rays refracted and dispersed downward.

In the drawing the letter *a* designates the lamp and *b* is a lens which is held in a frame *c* preferably ring shaped. To this frame is attached one end of a chain or wire *d* while the other end is hooked to screws or a ring on the globe of the lamp. The lens is preferably plano-convex shaped and is suspended below the light and the rays being thus diverged and at the same time magnified and refracted downward.

The flexible connections *d* in Fig. 1 are

shown suspended from a protector *e* of metal or strong material which prevents the screws *f* from coming into contact with or breaking any fragile part such as a glass chimney *g* or a shade or globe *h*.

The screws are inserted through a ring or crown part *i*. The chimney can be slipped or fitted into the protector and the shade can be seated on the protector.

If no protector is employed and the shade *h* is engaged directly by the screws *f* (Fig. 2) the flexible connections can be secured to a ring or hooks *k* between the shade *h* and the chimney suspended in the shade.

What I claim as my invention is:

1. A lamp comprising a chimney, a ring shaped protector at the upper end of said chimney means for connecting the protector to the chimney, a lens below the chimney and flexible connections extending unbrokenly from the protector to the lens so as to hold the lens a suitable distance below the chimney to allow ventilation.

2. A lamp comprising a chimney, a ring shaped protector surrounding the chimney, a crown, there being apertures in the crown, screws extending through the apertures in the crown and abutting against the protector for clamping the latter to the chimney, a lens and connections free from the globe extending unbrokenly from the protector to the lens to hold the latter a suitable distance below the chimney.

In testimony whereof I have hereunto set my hand in the presence of two subscribing witnesses.

LEOPOLD STIASSNY.
